UNITED STATES PATENT OFFICE.

DAVID G. McCAA, OF LANCASTER, PENNSYLVANIA, ASSIGNOR OF ONE-THIRD TO FEDERAL TELEGRAPH COMPANY, OF SAN FRANCISCO, CALIFORNIA, A CORPORATION OF CALIFORNIA.

METHOD OF AND APPARATUS FOR ELECTRICAL COMMUNICATION.

Application filed January 19, 1920. Serial No. 352,463.

To all whom it may concern:

Be it known that I, DAVID G. McCAA, a citizen of the United States, residing in the city of Lancaster, county of Lancaster, State of Pennsylvania, have invented a new and useful Method of and Apparatus for Electrical Communication, of which the following is a specification.

My invention relates to a method of and apparatus for electrically communicating signals or intelligence, telegraphically, telephonically or otherwise, by recourse to high frequency waves which may be transmitted over a conductor system extending between stations or, and principally, which are converted into electro-radiant energy transmitted through the natural media between stations.

It is the object of my invention to provide a method of and apparatus for electrical communication of the character referred to which shall render practically harmless or substantially eliminate the effect of natural electricity, as atmospheric disturbances, static, strays, damped waves from radio transmitters employing spark gaps, or other interfering electrical effects.

In some of its aspects my invention is similar or contains features germane to my prior application Serial Number 842,355, filed December 4, 1919.

For an illustration of some of the various forms my apparatus may take, and for an understanding of my method, reference is had to the accompanying drawings, in which:

Fig. 1 is a diagrammatic view of transmitting apparatus.

Fig. 2 is a diagrammatic view of receiving apparatus.

Referring to Fig. 1, A represents generically any transmitting conductor, as an antenna, of open circuit, loop, coil, or any other suitable type, or a line conductor extending to the receiving station.

Between the antenna and the earth E is connected the variable loading or tuning inductance L and the secondary of an oscillation transformer T, whose primary is in the anode circuit of the thermionic or electronic oscillator V comprising the anode a,

grid g, and incandescent cathode or filament f, the latter supplied with current from battery b and whose strength is regulated by resistance r. In the anode circuit is the battery B, which may be shunted by the condenser C, and a coupling coil L¹ in inductive relation with the coil L² in the grid circuit, an adjustable condenser C¹ being associated with the parts described for causing production of oscillations of any desired frequency, for example, radio frequency, and for purposes of illustration may be assumed to be 200,000 per second. A second electronic or thermionic oscillator V¹ has in its anode circuit the battery B¹, which may be shunted by the condenser C², a telegraphic key k, the coupling coils L³ and L⁴, variable condenser C³ and the primary of the oscillation transformer T¹ whose secondary is in the circuit of the grid g of the oscillator V, a variable tuning condenser C⁴ being connected in parallel with the secondary of the transformer T¹.

The oscillator V¹ produces modulating oscillations of frequency above audibility, for example, 20,000 per second. When the signaling key k is closed, the potential of the grid g of oscillator V is accordingly periodically varied at 20,000 per second, whereby there is impressed upon the transmitting medium by transformer T oscillations of a frequency of 200,000 per second varying in amplitude at modulator frequency, to wit, 20,000 per second.

For purposes of telephony, the key k may be kept permanently closed and the switch s closed, whereby the microphone m, in circuit with the battery b¹ and the primary of a transformer T², may cause the secondary of that transformer, which may be shunted by the variable tuning condenser C⁵, to vary the potential of the grid g of the modulator oscillator V¹ in accordance with speech. The result is that the transformer T impresses upon the transmitting medium oscillations of 200,000 frequency varying in amplitude at modulator frequency, 20,000 per second, and varying in amplitude also in accordance with speech.

Referring to Fig. 2, A represents a receiving conductor or antenna, of any suit-

able type including those hereinbefore referred to, or a line conductor extending from the transmitting station. When it is an antenna or the like, its path may be tuned by 5 the inductance L between which and earth E is connected the primary of the oscillation transformer T^3 . The antenna path is preferably tuned to the frequency of the energy transmitted, for example, 200,000 per second. 10 The secondary circuit of the transformer T^3 is also preferably tuned to the same frequency, as by tuning inductance L^5 and capacity C^6 , associated with the grid circuit of the thermionic or electronic detector V^2 in whose anode circuit is the battery B^2 and the primary of the transformer T^4 , current waves of modulator frequency, 20,000 per second, being produced in the primary and secondary of the transformer T^4 . 15

20 In the secondary circuit are connected the primaries P^1 and P^2 , so wound or connected that they both produce at their right ends, at a given instant, the same polarity, for example, south poles. Inductively related with 25 these primaries, respectively, are the secondaries S^1 and S^2 , with which are connected, respectively, the grids g and g^1 of thermionic devices whose electrodes may be in the same or different evacuated tubes. In 30 the example illustrated, the thermionic device V^3 has a single vacuum containing the aforesaid grids, with which are associated, respectively, the anodes a and a^1 , with a common filament f whose one terminal is 35 connected through both the secondaries S^1 and S^2 . In the anode circuits are connected the battery B^3 and the primaries P^3 and P^4 of a transformer T^5 , these primaries being 40 opposed to each other in their inductive effect upon the secondary S^3 , in circuit with which is connected the telephone P_h .

Also inductively coupled with the transformers S^1 and S^2 , respectively, are the coils P^5 and P^6 so wound or connected that at the 45 same instant they exhibit at their left ends different polarities. These coils are in the circuit of the grid g of the thermionic oscillator V^4 in whose anode circuit is the battery B^4 , which may be shunted by the condenser C^7 , and the coupling coils L^6 and L^7 , a variable tuning condenser C^8 being 50 connected across the grid and filament.

The operation is as follows:

With the transmitter impressing upon the 55 medium intervening between the transmitting and receiving stations undamped waves, varying in amplitude at frequency above audibility, there are produced in the secondaries S^1 and S^2 currents of modulator 60 frequency, for example, 20,000 per second; but they simultaneously similarly affect the grids g and g^1 so that like currents simultaneously traverse the primaries P^3 and P^4 which, since they are differential in their action, produce no inductive effect upon the

secondary S^3 , and nothing is heard in the telephone P_h , unless the oscillator V^4 is in operation producing oscillations of a frequency of 21,000 per second, for example, 70 whereby there are produced in the circuits of the grids g and g^1 of the thermionic device V^3 beats of audible frequency, 1,000 per second, but dephased with respect to each other by practically 180 degrees, causing in the primaries P^3 and P^4 currents dephased 75 substantially 180 degrees, which, however, because of the differential winding or connection of the primaries P^3 and P^4 , cumulatively affect the secondary S^3 producing in the telephone P_h an audible note having a 80 frequency of 1,000 per second, which note appears for long and short periods according to the length of time the key k at the transmitter is depressed to form dots and dashes. 85

Or for telephony, with the key k closed, switch s closed and the microphone m spoken into, there will be transmitted, as stated, undamped waves modulated in amplitude at modulator frequency, as 20,000 90 per second, and varying in amplitude also in accordance with speech.

At the receiver, for telephony, the oscillator V^4 will be set to produce current of such 95 frequency that the beats produced in reaction in the secondary coils S^1 and S^2 with the modulator frequency of 20,000 per second, will be above audibility. In such case, the beats operate cumulatively upon the secondary S^3 , but being inaudible, will produce no effect in the telephone P_h ; but the envelope of these inaudible beats represents speech, which will be reproduced by the telephone P_h . 100

In the case of both telephony and telegraphy, or other mode of signaling by the method and apparatus described, the effects of static, natural electricity, strays, or damped waves from transmitting apparatus employing a spark gap, will have no disturbing or interfering effect upon the transmission of the signals or messages for the reasons explained in my aforesaid application Serial Number 342,355; that is, because the interfering effects balance out as to the secondary S^3 because of the differential effects of the primaries P^3 and P^4 for all simple detector effects, as distinguished from beat effects caused by the tube B^4 . 115

By modulating the transmitted energy 120 whereby it comprises undamped waves varying in amplitude at predetermined frequency above audibility, the possibility of interference by natural atmospheric effects or other transmitting stations, especially when radiating damped waves, is further reduced, because the disturbing impulses or effects cannot produce substantial effects of modulator frequency, for example, 20,000 per second, 125 and such effects as are so produced are pre- 130

vented from affecting the telephone by the differential primaries P^3 and P^4 .

What I claim is:

1. The method of electrically transmitting intelligence, which consists in producing high frequency oscillations, modulating the amplitude thereof at a constant frequency above audibility, controlling the same to represent the intelligence to be transmitted, impressing the energy upon a transmitting medium, receiving the energy from said transmitting medium and effecting thereby current of said constant modulation frequency, impressing said current upon different paths whose joint effect upon a translating instrument is substantially nil, causing to react with said current locally produced current waves of frequency producing equal and opposite beats of constant frequency, and causing said beats to affect said signal translating instrument cumulatively.

2. The method of electrically transmitting intelligence, which consists in producing high frequency oscillations, modulating the amplitude thereof at a constant frequency above audibility, controlling the same to represent the intelligence to be transmitted, impressing the energy upon a transmitting medium, receiving the energy from said transmitting medium and effecting thereby current of said modulation frequency, impressing said current upon different paths whose joint effect upon a translating instrument is substantially nil, causing to react with said current locally produced current waves of frequency producing equal and opposite audible beats of constant frequency, and causing said beats to affect said signal translating instrument cumulatively.

3. The method of receiving intelligence represented by waves of radio frequency varying in amplitude at a constant frequency above audibility, which consists in effecting by the received energy current of said second named frequency, impressing said current upon different paths whose joint effect upon a translating instrument is substantially nil, causing to react with said current locally produced current of different frequency to produce substantially equal and opposite beats of constant frequency, and causing said beats to affect said signal translating means cumulatively.

4. The method of receiving intelligence represented by waves of radio frequency varying in amplitude at a constant frequency above audibility, which consists in effecting by the received energy current of said second named frequency, impressing said current upon different paths whose joint effect upon a translating instrument is substantially nil, causing to react with said current locally produced current of

different frequency to produce substantially equal and opposite beats of constant audible frequency, and causing said beats to affect said signal translating means cumulatively.

5. A system for electrically transmitting intelligence comprising means for producing high frequency oscillations, means for varying the amplitude of said oscillations at predetermined frequency above audibility, means for controlling the energy in accordance with the intelligence to be transmitted, and receiving apparatus comprising means for effecting by the received energy current of said predetermined frequency, a signal translating instrument, means for rendering the direct effect of said current upon said instrument substantially nil, means for producing oscillations of a frequency different from said predetermined frequency, means causing said oscillations to react with said current to produce substantially equal and opposite beats of constant frequency, and means for subjecting said translating instrument to the cumulative effects of said beats.

6. Apparatus for receiving intelligence represented by high frequency energy varying in amplitude at predetermined frequency, comprising a rectifier producing current of said predetermined frequency, a plurality of paths inductively affected by said current, a signal translating instrument differentially affected by said paths, means for producing oscillations different from the frequency of said current, means for oppositely inductively affecting said paths by said oscillations whereby equal and opposite beats of constant frequency are produced in said paths, said beats cumulatively affecting said translating instrument.

7. Apparatus for receiving intelligence represented by high frequency energy varying in amplitude at predetermined frequency, comprising a receiving conductor, means associated therewith for effecting a current of said predetermined frequency, transformer primaries traversed by said current, detector circuits coupled with said primaries, opposing windings associated, respectively, with said detector circuits, a source of oscillations oppositely coupled with said detector circuits and reacting with the current therein to produce substantially equal and oppositely beats of constant frequency, whereby said opposing windings operate cumulatively respecting the beat energy.

8. Apparatus for receiving intelligence represented by high frequency energy varying in amplitude at predetermined frequency, comprising a receiving conductor, means associated therewith for effecting a current of said predetermined frequency, transformer primaries traversed by said current, detector circuits coupled with said

primaries, a second transformer having opposing primary windings associated, respectively, with said detector circuits, a signal translating instrument associated with the 5 secondary of said second transformer, and a source of oscillations oppositely coupled with said detector circuits and reacting with

the current therein to produce substantially equal and opposite beats of constant frequency.

In testimony whereof I have hereunto affixed my signature this 16th day of January, 1920.

DAVID G. McCAA.
